VANITY CASE

Clarence V. Johnson, Yates Center, Kans.

Application August 27, 1951, Serial No. 16,454

Term of patent 7 years

(Cl. D86—10)

To all whom it may concern:

Be it known that I, Clarence V. Johnson, a citizen of the United States of America, residing at Yates Center, Woodson County, and State of Kansas, have invented a new, original, and ornamental Design for a Vanity Case, of which the following is a specification, reference being had to the accompanying drawing, forming a part thereof.

Figure 1 is a front elevational view of my vanity case in closed position, showing my new design;

I claim:

The ornamental design for a vanity case, as shown.

CLARENCE V. JOHNSON.
